SPHYGMOMANOMETER

Isidor Laufman and Arthur L. Laufman,
New York, N. Y.

Application October 18, 1934, Serial No. 748,810

6 Claims. (Cl. 73—44)

Our present invention relates generally to measuring instruments, and has particular reference to an improved sphygmomanometer.

The primary object of our invention is to provide a device whereby the blood pressure of a subject at any given moment may be determined with great facility and without requiring the attendance or assistance of any person other than the subject, himself. While it is contemplated that the present invention will lend itself readily to the production of a coin-operable apparatus (thereby permitting any person to ascertain his own blood pressure at any given time by proper insertion of a suitable coin and by performance of certain specified steps), nevertheless it will be understood that the invention is by no means restricted to any such utility. In many instances, for example, it may be found highly desirable to use the present apparatus in clinics, hospitals, or even in individual doctors' offices.

One of the outstanding advantages of our present device lies in its ability to register, with great reliability, the true blood pressure of a subject at any given instant. Ordinary methods of taking blood pressure, and other devices heretofore devised for such purpose, are subject to a serious disadvantage arising from the possibility of error due to inadvertent and irrelevant movements by the subject. The present device, on the other hand, is so constructed and arranged, and is provided with special means, that it assures a proper and correct registration of blood pressure at any given time, even where the apparatus is caused to function by a person wholly unfamiliar with the true nature of the pressure he is seeking to ascertain.

The device is, in major respects, similar in kind to that which is customarily employed by physicians. It consists of an inflatable bladder applicable to the arm of a subject, a manometer gauge in permanent communication with the bladder, a means for inflating the bladder, and a slow-leaking vent for the bladder. The bladder is first inflated to a degree which totally impedes the flow of blood; and as the air escapes through the slow-leaking vent, the pressure recorded by the manometer gauge gradually falls. At the instant of time when the pressure has been reduced just sufficiently to permit the flow of blood to be reestablished, a fluctuation in pressure takes place, and the manometer gauge indicates such fluctuation.

One of the features of our invention lies in providing a means wholly independent of the

slow-leaking vent for preventing escape of air through such vent. If the escape of air is prevented at the time the blood flow has been re-established, the gauge will continue to fluctuate indefinitely; but, on the other hand, if the escape of air through the vent is prevented at any other time, the gauge will not fluctuate. This additional means for preventing the escape of air through the slow-leaking vent is thus a reliable means for verifying the results of the determination in question.

A further feature of our invention lies in the provision of a device for automatically producing a signal, preferably a momentary audible signal, whenever the gauge is registering a rise in pressure. This serves as an additional means for verifying the results, because, when the gauge is correctly registering the blood pressure of a subject the audible signal can be caused to operate in timed relation to the pulsations of blood through the blood vessels of the subject.

A further feature of our invention lies in the provision of a specially constructed device for automatically sealing the bladder when it is tightened upon the arm of a subject, and for automatically permitting a rapid release of the air in the bladder when the arm of a subject is withdrawn. This serves automatically to place the apparatus, with great rapidity, into proper condition for the next test, thereby avoiding any reliance upon the subject or subjects to restore the parts to their normal conditions.

Other features of our invention will be more fully appreciated after this specification has been read, and include the provision of an attractive structural arrangement of parts whereby the device can be inexpensively manufactured and assembled, and readily dismantled or disassembled for purposes of inspection or repair; the provision of a pump which is readily operable by even an inexperienced person; the provision of a means for preventing too speedy an inflation of the bladder, thereby safeguarding the device from intentional or inadvertent abuse; and the provision of an apparatus, generally, which is substantially foolproof, staunch, compact, and reliable.

We achieve the foregoing objects, and such other objects as may hereinafter appear or be pointed out, in the manner illustratively exemplified in the accompanying drawings, wherein—

Figure 1 is a perspective view of an apparatus of the present character;

Figure 2 is an enlarged cross-sectional view

55

taken substantially along the line 2—2 of Figure 1;

Figure 3 is an enlarged cross-sectional view taken substantially along the line 3—3 of Figure 1;

Figure 4 is a fragmentary cross-sectional plan view taken substantially along the line 4—4 of Figure 3; and

Figure 5 is a diagrammatic view showing the relationship of the various parts.

Referring for the moment to Figure 5, the substantially rectangular rubber bladder 10 is of a kind which is adapted to be encircled around the forearm of a subject. By means of a cloth or similar lining 11, the bladder is held in superposed relation to a leather backing 12, the latter being rolled upon itself into the form of a loop through which the arm of the subject is inserted. More particularly, the rear end of the backing 12 is secured by screws 13 to a bracket 14, and the forward end of the backing develops into a leather strap 15 having a series of perforations 16 therein. The strap is preferably provided with the knob 17, and when the apparatus is set up the strap 15 extends through the slot 18, to complete the loop, and is ultimately disposed in substantially the position shown in Figures 1 and 2.

When the arm of a subject is inserted through the loop, as shown in Figure 1, the bladder is tightened around the arm by pulling upon the strap 15 and by then engaging a selected perforation with the movable complementary fastening element 19. The latter is hingedly mounted, as at 20, and is normally in the dot-and-dash position of Figure 2. The tightening of the strap automatically swings the element 19 into the full-line position of Figure 2, and this movement fulfills a function which will be presently described.

A conduit composed of the sections 21 and 22 establishes a permanent communication between the interior of the bladder 10 and the rear end of a U-tube manometer, which is preferably of glass. One arm 23 of the manometer is enlarged to serve as a sort of reservoir for a supply of mercury or similar liquid 24. The other arm 25 is mounted in vertical relationship in front of a backing 26 upon which suitable scale markings are provided.

The conduit between the bladder and gauge is provided with a slow-leaking vent in the form of an adjustable needle valve 27. This valve is set when the device is initially manufactured and subsequent adjustments are not contemplated, except for purposes of repair. The outlet end of the valve or vent terminates in a resilient, collapsible tube 28 composed, for example, of soft rubber. This tube is caused to have its end mounted in a block 29, and a movable pressure member, such as the pushbutton 30, is mounted so that it may be pressed against the tube 28 to collapse the latter and thereby squeeze it closed. The member 30 thus serves as a means wholly independent of the slow-leaking vent 27 to prevent escape of air through the vent 27.

The conduit between the bladder and gauge is further provided with the pressure-releasing outlet 31 which also terminates in a tube of resilient, collapsible material 32. This tube may be, for example, soft rubber, and its end is mounted in a block 33 and passes between one wall of this block and the movable element 19. The normal resilience of the tube 32 causes this outlet tube 75 normally to be open to the atmosphere, and

causes the element 19 to be normally pressed into the dot-and-dash position of Figure 2. When the bladder is caused to be tightened around the arm of a subject, the engagement of the element 19 presses the latter toward the right, and this pressure collapses the tube 32, as shown most clearly in Figure 2, whereby the outlet is sealed.

The inflation of the bladder is accomplished by means of a pump 34, which is similar, in character, to an ordinary bicycle pump and is provided with a piston 35 and a plunger 36. The latter terminates in the knob 37, and is provided further with the ratchet teeth 38. Engaging with one of these teeth is the releasable latch 39 which is normally urged into engagement with one of the teeth by means of a spring 40 (see Figure 4). The latch 39 is mounted on the end of a rod 41 which terminates in a projection 42. The latter is adapted to be encountered by the forward end of a coin slide 43 whenever the latter is capable of being shifted toward the left, i. e., into the dot-and-dash position of Figures 3 and 4.

The coin slide 43 forms part of a coin-operated mechanism which is designated generally by the reference numeral 44 and which will not be described in detail since its construction is well known, per se, and does not enter into the present invention. Suffice it to state that when a suitable coin 45 is inserted into the coin slide 43; the latter may be advanced toward projection 42, otherwise not; and during this advance the coin is caused to fall into a suitable collection box.

Beneath the piston 35 of the pump, a compression spring 46 is arranged, normally tending to urge the piston upwardly.

A conduit 47 extends from the pump to the conduit 21, and in accordance with our invention we arrange in this conduit a check valve 48 and an adjustable constricting valve 49. The valve 48 is obviously for the purpose of preventing air from flowing in the return direction after it has passed into the conduits 21 and 22. The valve 49 is for the purpose of constricting the speed with which air may be caused to flow from the pump 45 into the bladder.

At its upper end, the tube 25 of the gauge terminates in the enlarged chamber 50 which serves as a reservoird for accommodating excess liquid in the event that the liquid in the tube 25 is caused to rise too high. Communicating with the interior of the chamber 50 is a tube 51 which terminates in a tubular fitting 52 tilted upwardly by a very slight degree toward its open end. Within this fitting the steel ball 53 is mounted. Gravity causes this ball ordinarily to be positioned at the inner end of the fitting 52, but the smoothness of the ball and the snug fit of the ball within the fitting 52 permits the ball to be advanced to the left whenever there is an increase of pressure 60 within the tube 51. Immediately to the left of the fitting 52 we mount a bell or gong 54, so that whenever the ball is urged to the left it encounters the gong and causes an audible signal to be produced.

Beneath the fitting 52 is a chamber 55 which serves as a convenient overflow receptacle in the event that any of the liquid 24 should, by accident, be forced into the tube 51.

All of the mechanism is suitably supported and assembled within a framework which is preferably accommodated within a cabinet 56, as shown in Figure 1. Many of the various parts that have been hereinbefore described will be recognized in Figure 1. While the arrangement of parts is 75

a matter of preference and design, we prefer to have the coin slide 43 in the front wall of the cabinet; to mount the leather backing 12 on the top of the cabinet; to arrange the button 30 in an accessible position on the top of the cabinet; and to mount the manometer gauge within a casing 57 so that it will be approximately on a level with the eyes of the average person. The pump handle 37 is also arranged in an accessible position on top of the cabinet, and it will be understood that this handle is normally in the full line position of Figure 1.

The mode of operation of the apparatus is as follows. The person whose blood pressure is sought first inserts his forearm into the looped backing 12, as indicated in dot-and-dash lines in Figure 1; and the knob 17 is then grasped and pulled to the left, thereby tightening the bladder around the arm. During this procedure, the lining 11 may wrinkle somewhat, as indicated in Figure 2, but this wrinkling is purposely provided for, so as to keep the bladder 10 concealed and protected at all times. The bladder is secured in tightened relationship around the arm by engaging a selected perforation 16 over the movable element 19. This automatically causes the element 19 to swing toward the right and seal the pressure-release outlet 31.

The subject then places a proper coin in the slide 43, and when the slide is pushed in the latch 39 releases the pump rod 36, causing it to jump upwardly, under the action of the spring 46, into the dot-and-dash position of Figure 1.

The handle 37 is then pressed downwardly, whereby the bladder becomes inflated. The speed of inflation is limited by the constricting valve 49 which prevents the operator from either intentionally or inadvertently forcing the piston of the pump downwardly at too great a speed. During the inflation of the bladder, the liquid 24 rises in the gauge glass 25, and suitable directions attached to the machine will instruct the user to inflate the bladder until a certain predetermined gauge reading is reached. The pressure thus specified will be one which is well above any conceivable blood pressure, as a result of which the flow of blood through the arm of the subject will be completely impeded.

After the pump handle has been pushed downwardly to inflate the bladder, it remains in its downward position by virtue of the locking latch 39.

Since the slow-leaking vent 27 is constantly open, the inflation of the bladder gradually lessens and the observer will be able to note a gradual falling of the liquid in the gauge glass 25. At the instant when the pressure has fallen just sufficiently to permit the flow of blood to be reestablished, the pressure in the bladder will momentarily increase because of the expansion of the blood vessel in the arm. This will cause the liquid in the column 25 to bob up and down rhythmically. The level at which this occurs can be read upon the scale 26, and is a measure of the blood pressure of the subject.

During the up-and-down movement of the liquid, the ball or member 53 will be caused to oscillate back and forth in the fitting 52, thereby causing an audible signal to be produced. With the device herein illustrated, each pulsation of the blood in the subject's arm will cause a momentary ringing of the bell 54.

After the desired measurement has been ascertained, it is a relatively simple matter to release the strap 15 from the element 19, thereby

loosening the bladder from the arm. The subject then withdraws his arm, and the release of the element 19 produces an instantaneous release of all the pressure in the system. The apparatus is then immediately ready for the succeeding subject or test. 5

From the foregoing, it will be understood that the purpose of observing the gauge is to note the point at which the liquid commences to bob up and down. It frequently happens that voluntary or involuntary movements of a digit, hand, or other parts of the subject, occasioned, for example, by tremor or ticks, or by a cough or a sneeze, will cause a momentary "bobbing" of the liquid in the gauge. To prevent such an incident from causing the user of the apparatus to draw an erroneous conclusion as to the blood pressure being measured, it is merely necessary for the user to press down upon the button 30 whenever the liquid commences to bob. If the bobbing of the liquid is due to any cause other than a reestablishment of blood flow in the arm of the subject, pressure upon the button 30 will cause the liquid in the column 25 to halt completely. An erroneous reading can thus be definitely recognized as such, and disregarded. If, on the other hand, the button 30 is pressed down during a fluctuation of the liquid, which properly measures the blood pressure of the subject, a sealing of the vent will have no effect upon the 30 fluctuations, and the liquid 24 will continue to bob up and down rhythmically, causing the audible signal to function each time there is a rise in pressure registered upon the gauge. The true measurement that is sought can thus be verified. 35

It will be understood that our invention is not necessarily restricted to the specific detailed construction of parts, as herein illustrated by way of example, nor to the specific arrangement of such parts or mode of assembly, as herein shown. 40

In general, it will be understood that changes in the details, herein described and illustrated for the purpose of explaining the nature of our invention, may be made by those skilled in the art without departing from the spirit and scope 45 of the invention as expressed in the appended claims. It is, therefore, intended that these details be interpreted as illustrative, and not in a limiting sense.

Having thus described our invention, and illustrated its use, what we claim as new and desire to secure by Letters Patent is—

1. In a sphygmomanometer, a manometer gauge, a bladder in permanent communication with the gauge, a slow-leaking vent and a normally open, rapid release outlet for the bladder, means for inflating the bladder, means for tightening the bladder around a subject's arm, and a device automatically operable by said tightening means for sealing said outlet. 55

2. In a sphygmomanometer, a manometer gauge, a bladder in permanent communication with the gauge, a slow-leaking vent and a normally open, rapid release outlet for the bladder, means for inflating the bladder, means for tightening the bladder around a subject's arm, means for sealing said outlet when the bladder is in position, and means independent of the slow-leaking vent for preventing the escape of air through said vent. 65

3. In a sphygmomanometer, a manometer gauge, a bladder in permanent communication with the gauge, a slow-leaking vent and a normally open, rapid release outlet for the bladder, means for inflating the bladder, means for tight- 70
75

ening the bladder around a subject's arm, a device automatically operable by said tightening means for sealing said outlet, and means independent of the slow-leaking vent for preventing the escape of air through said vent.

4. In a sphygmomanometer, a manometer gauge, a bladder in permanent communication with the gauge, a slow-leaking vent and a normally open, rapid release outlet for the bladder, means for inflating the bladder, means for tightening the bladder around a subject's arm, said means including cooperable fastening elements one of which is necessarily moved when the bladder is tightened, and a device automatically operable by said movable element for sealing said outlet.

5. In a sphygmomanometer, a manometer gauge, a bladder in permanent communication with the gauge, a slow-leaking vent and a normally open, rapid release outlet for the bladder,

means for inflating the bladder, means for tightening the bladder around a subject's arm, said means comprising a perforated strap and a movable element adapted to engage in a selected perforation when the bladder is tightened, and a device automatically operable by said movable element for sealing said outlet. 5

6. In a sphygmomanometer, a manometer gauge, a bladder in permanent communication with the gauge, a slow-leaking vent for the bladder, means for inflating the bladder, means for tightening the bladder around a subject's arm, and means independent of the slow-leaking vent for preventing the escape of air through said vent, said last-named means comprising a re- 15 silent, collapsible vent tube, and a pressure member mounted for movement against said tube so as to collapse the latter.

ISIDOR LAUFMAN.
ARTHUR L. LAUFMAN. 20
